FLUID PRESSURE BRAKE

Ellis E. Hewitt, Edgewood, Pa., assignor to The Westinghouse Air Brake Company, Wilmerding, Pa., a corporation of Pennsylvania

Application June 30, 1934, Serial No. 733,181

43 Claims. (Cl. 303—40)

This invention relates to locomotive fluid pressure brake equipments and more particularly to that type of equipment which includes a distributing valve device such as is fully disclosed in the application of Clyde C. Farmer and myself, Serial No. 619,052, filed June 24, 1932, or in the application of Charles H. McKinstry, Serial No. 690,685, filed September 23, 1933.

The former standard fluid pressure brake equipment for locomotive and cars was designed for handling a train of a length up to around eighty cars. In recent years, however, trains of more than eighty cars have been operated on various railroads.

As a consequence of the increased length of trains, it has become increasingly difficult to properly control the application and release of the brakes and especially to so control an application of the train brakes as to insure the gentle gathering or closing of the slack in the train.

It is well known that, with this type of equipment, when the engineer's brake valve device is turned to either service or emergency position, the brakes apply serially from the front of the train toward the rear of the train, that is to say, the locomotive brakes will apply first and then the brakes on the cars will apply serially toward the rear end of the train. As a result of this serial brake action, the deceleration of the locomotive begins before the brakes on the cars become effective.

There is a certain amount of slack or lost motion in the usual coupling mechanisms between the adjacent ends of adjacent cars of the train, and by reason of the fact, as above explained, that the locomotive begins to decelerate before the cars, this slack will permit the cars to run in against the slower moving locomotive, thus the locomotive will contribute to the harsh gathering or closing of the slack in the train.

It is very desirable to avoid the above described slack gathering or closing action when an application of the brakes is initiated, and to obtain this result, means such as is disclosed in the aforementioned prior pending application of Clyde C. Farmer and myself, Serial No. 619,052 have been employed for synchronizing the application of the locomotive and car brakes, in other words for causing the locomotive brakes to apply at substantially the same time as the car brakes begin to apply effective braking force. This of course requires the delaying of the application of the locomotive brakes for a short period of time following the initiation of a brake pipe reduction.

In the pending application just referred to, Se-

rial No. 619,052, the delay of the application of the locomotive brakes is accomplished by delaying the movement of the equalizing portion of the locomotive distributing valve device to service application position and this delay is accomplished by reducing the pressure in the pressure chamber of the device. This reduction is effected by venting fluid under pressure from the pressure chamber to a reduction reservoir or chamber when the equalizing portion has moved a short distance toward application position upon the reduction in brake pipe pressure, the slide valves of the device establishing the communication through which fluid is vented from the pressure chamber. After a reduction in the pressure of the pressure chamber, say for instance around four or five pounds, has been effected, a cut-off valve subject to the pressure of fluid in the reduction chamber operates to cut off the flow of fluid from the pressure chamber to the reduction chamber, thus limiting the reduction to a chosen degree. Now when the brake pipe pressure reduces sufficiently below the reduced pressure in the pressure chamber to create a sufficient fluid pressure differential on the piston of the equalizing portion to cause the piston and associated slide valves to move to application position, an application of the locomotive brakes is effected.

While the above described distributing valve device does function to produce the desired synchronization of the application of the locomotive brakes with the application of the car brakes in the desired manner, it has been found in some instances, where certain manufacturing inaccuracies exist in the device, the resistance offered by the several movable parts to movement to service application position is considerably in excess of that intended and that, as a consequence, an excessive reduction in brake pipe pressure is required to create a sufficient fluid pressure differential on the equalizing piston to cause it to operate to shift the equalizing slide valves to service application position. It will here be understood that the equalizing piston is intended to move the equalizing slide valves from the pressure chamber venting position when the brake pipe pressure has been reduced sufficiently to create a fluid pressure differential of about one and one-half pounds on the equalizing piston, whereas, in a device embodying the above mentioned inaccuracies, the required fluid pressure differential may be as great as four or five pounds, and as a consequence of this, the application of the locomotive brakes will be unduly delayed, so that the car brakes will apply with an effective

braking force before the locomotive brakes apply. This will permit the locomotive to move forwardly relative to the braked cars and cause run out shocks which may be severe enough to 5 break or otherwise damage either the coupling mechanism between the locomotive and cars or the coupling mechanism between cars at the head end of the train.

One object of the present invention is to provide an improved locomotive fluid pressure brake equipment which will function to provide the desired synchronization of the locomotive brakes with those on the cars of a train and yet be free of the aforementioned difficulties.

Another object of the invention is to provide a distributing valve device of the type disclosed in the aforementioned pending application Serial No. 619,052 having improved means for delaying the start of a service application of the locomotive brakes in which the equalizing portion of the device is caused to move to application position upon the initiation of a reduction in brake pipe pressure, to establish a communication through which fluid under pressure is vented 25 from the pressure chamber to the reduction chamber by way of the reduction limiting valve mechanism, and in which the reduction limiting valve mechanism responds to a chosen reduction chamber pressure to close off the flow of fluid 30 to the reduction chamber to limit the reduction in pressure chamber pressure to a chosen degree, and to then establish a communication through which fluid under pressure flows from the pressure chamber to the application chamber and application piston chamber to cause the application portion to supply fluid under pressure to the locomotive brake cylinders.

The fundamental differences between the hold-back feature of the equipment of the present application and that of the aforementioned pending application Serial No. 619,052, are as follows: in the present equipment the reduction in pressure chamber pressure is effected when the equalizing portion of the distributing valve device is moved 40 to service application position and the supply of fluid for actuating the application portion to supply fluid under pressure to the locomotive brake cylinders is controlled by the reduction limiting and control valve mechanism and by the 45 equalizing portion. In the equipment of said pending application the reduction in pressure chamber pressure is effected when the equalizing portion is moved to a position between release position and service application position 50 and the supply of fluid for actuating the application portion to supply fluid under pressure to the brake cylinders is controlled by the equalizing portion only.

It will be understood that when the equalizing portion of the latter equipment is in pressure chamber venting position, the pressure of fluid in said chamber is reduced the desired amount, (about five pounds). A corresponding reduction in brake pipe pressure will only balance the pressures on opposite sides of the equalizing piston, so that the equalizing portion will remain in this venting position until a sufficient fluid pressure differential is created to move it to service application position. If the fluid pressure differential required to move the equalizing portion to service application position is four pounds, then it will require a further reduction in brake pipe pressure of at least four pounds to create such differential. It will thus be seen that a reduction 70 in brake pipe pressure of approximately nine 75 pounds is required to cause the equalizing portion to move to service application position in which the equalizing portion supplies fluid under pressure from the pressure chamber to the application piston chamber to cause the application portion to function to supply fluid under pressure to the locomotive brake cylinders.

5 pounds is required to cause the equalizing portion to move to service application position in which the equalizing portion supplies fluid under pressure from the pressure chamber to the application piston chamber to cause the application portion to function to supply fluid under pressure to the locomotive brake cylinders.

In the equipment of the present application, if the resistance offered by the several movable parts of the equalizing portion is the same as that offered by the corresponding parts of the equipment just referred to in the preceding paragraph, the equalizing portion will move to service application position upon a four or five pound reduction in brake pipe pressure and in this position 10 effects the reduction in pressure chamber pressure and establishes a communication through which fluid under pressure is adapted to be supplied to the application piston chamber of the application portion. This communication is, however, maintained closed by the reduction limiting and control valve mechanism until such time as the required reduction in pressure chamber pressure has been effected. When the required reduction is effected, the reduction limiting and control valve mechanism responds to the pressure of the reduction reservoir to close off the flow of fluid from the pressure chamber to the reduction chamber, and at substantially the same time, opens the communication from the 20 pressure chamber to the application piston chamber and fluid supplied through this communication, causes the application portion to function to supply fluid under pressure to the locomotive brake cylinders.

30 From the above comparison it is obvious that since the reduction in pressure chamber pressure in the present equipment is not effected until the equalizing portion has been moved to service application position, the equalizing portion will move to this position upon a much lighter reduction in brake pipe pressure than is required in the equipment of the pending application where the reduction in pressure chamber pressure is effected before the equalizing portion is moved to service application position and where this reduction retards the movement of the equalizing portion to application position. Thus in the equipment of the present application, an undue delay 35 of a service application of the locomotive brakes is avoided.

In effecting an emergency application of the brakes the service application hold-back means of the equipment of the present application and of the equipment of the aforementioned pending application Serial No. 619,052 is ineffective to 40 materially delay the application of the locomotive brakes, and since it is highly desirable to avoid the harsh run in of the slack in the train when an emergency application of the brakes is effected 45 some means must be provided for preventing such action.

To obtain this result means have heretofore been proposed for holding back the application of the locomotive brakes for a period of time after a reduction in brake pipe pressure is initiated, so that, during the period of time that the slack in the train is gathering or closing, the inertia of the locomotive will tend to keep the slack 50 stretched out.

70 As disclosed in the aforementioned pending application of Charles H. McKinstry, Serial No. 699,685, means have also been proposed which, when an emergency reduction in brake pipe pressure is initiated, so controls the rate of increase 75

in the locomotive brake cylinder pressure that it will not exceed the rate of increase in brake cylinder pressure on the cars of the train. On a short train where the train slack is not very great and its rapid gathering or closing will not cause damaging shocks, the proposed brake cylinder build up controlling means may be rendered ineffective, and to do this, manually operable means has been shown in said pending application.

The brake cylinder pressure build-up control means disclosed in the above mentioned application of Charles H. McKinstry is embodied in the equipment disclosed in the present application, and another object of the invention is to provide pneumatically controlled means for rendering the brake cylinder pressure build-up control means either effective or ineffective to control the rate of increase in locomotive brake cylinder pressure, and a further feature resides in the provision of manually operable means readily accessible to the engineer for controlling the operation of the pneumatically controlled means to selectively render the brake cylinder pressure build-up control means effective or ineffective.

Other objects and advantages will appear in the following more detailed description of the invention.

In the accompanying drawings, Fig. 1 is a dia-
30 grammatic view, partly in section, of a locomotive fluid pressure brake equipment embodying the invention; Fig. 2 is an enlarged diagrammatic sectional view of the distributing valve device, the several parts being shown in release position; Fig. 3 is a fragmentary diagrammatic sectional view of the distributing valve device showing the equalizing portion in service application position and the reduction limiting and control valve mechanism in its pressure chamber
35 venting position; Fig. 4 is a fragmentary dia-
grammatic sectional view showing the reduction limiting and control valve mechanism in service application position; Fig. 5 is a fragmentary diagrammatic sectional view showing the equalizing portion of the distributing valve device in emergency application position; Fig. 6 is a de-
40 velopment view of the automatic brake valve device; and Fig. 7 is a diagrammatic view of a train consisting of a locomotive, tender and two cars.

50 As shown in Fig. 1 of the drawings, the locomotive fluid pressure brake equipment may comprise a main reservoir 1, a feed valve device 2, an automatic brake valve device 3, an independent brake valve device 4, a brake pipe 5, a distributing valve device 6, a brake cylinder 7, an emergency change-over brake cylinder pressure build-up control valve device 8, and a manually operable valve device 9 for controlling the operation of the control valve device 8.

60 The distributing valve device 6, with the exceptions which are hereinafter particularly pointed out, is substantially the same in construction and function as the distributing valve device disclosed in the aforementioned pending application 619,052. In view of this a somewhat simplified form of distributing valve device is shown in the drawings.

The distributing valve device shown in the drawings comprises an equalizing portion 10, an application portion 11, a reduction limiting and control valve device 12, a release valve device 13 and a safety valve device 14.

The equalizing portion 10 comprises a piston 15 having at one side a piston chamber 16 which is connected through a passage and pipe 17 to the

brake pipe 5, and having at its other side a valve chamber 18 containing a main slide valve 19 and an auxiliary slide valve 20 adapted to be operated by the piston 15 through the medium of a stem 21 with which the piston is provided. It will here 5 be noted that the seat for the main slide valve 19 is formed on the upper side of the valve chamber 18 and the slide valves 19 and 20 are positioned to suit, but in practice the seat will be located at the bottom of the chamber and the 10 slide valves arranged in the usual manner. The reason for showing the seat and slide valves in this manner is to eliminate, in so far as possible, the tortuosity of the many passages leading to the slide valve seat, thus materially simplifying 15 the showing of the invention.

One end of the slide valve chamber 18 is de-
20 fined by a cap member 22 having screw-threaded connection with the casing of the distributing valve device, said cap member together with the 20 casing defining a chamber 23 which is in constant open communication through a passage 24 with the valve chamber 18 and through a passage 25 with a pressure chamber or reservoir 26.

The outer end of the piston chamber 16 is 25 closed by a cap member 27, a gasket 28 being clamped between the member and casing to prevent leakage of fluid under pressure from the chamber to the atmosphere. A portion of this gasket extends into the piston chamber, against 30 which portion the equalizing piston 15 is adapted to seal when the piston is moved to emergency position.

Slidably mounted in the cap member 27 is a 35 piston stop 29 which is urged inwardly toward the equalizing piston 15 by the action of a coil spring 30, the inward movement of the stop being limited by the engagement of a flange 31 thereof with the cap member as shown in Fig. 2.

The application portion 11 of the distributing 40 valve device comprises an application piston 32 having at one side an application piston chamber 33 and at the other side a chamber 34. The piston 32 is provided with a baffle piston 35 which is slidably mounted in a suitable bore in the 45 casing and which is disposed between the chamber 34 and a valve chamber 36 containing a brake cylinder exhaust valve 37 which is adapted to be operated by means of a stem 38 with which the application piston is provided. The valve chamber 50 36 is in constant open communication through a passage and pipe 39 with the brake cylinder 7 and also with the chamber 34 through passage 39, a branch passage 41 and the passage in a choke plug 42 having screw-threaded connection 55 with the casing.

The application piston 32 besides being adapted to shift the brake cylinder exhaust valve 37, is also adapted to control the operation of a brake cylinder supply valve device 43. This supply valve 60 device comprises a casing which is secured to the casing of the application portion 11, and which is provided with an interior annular guide 45 in which is slidably mounted a valve piston 46 having a gasket 47 mounted in one end thereof for engagement with an annular seat rib 48 surrounding a passage extending through one end of the casing and leading to the exhaust valve chamber 36. The casing of the device together with the valve piston 46 define chambers 59 and 51 65 which are in constant open communication with each other through a passage 52 in the casing. Contained in the chamber 59 is a spring 53 which is adapted to urge the valve piston into sealing engagement with the seat rib 48. The chamber 70 75

51 is in constant open communication through a passage and pipe 54 with the main reservoir 1.

The reduction limiting valve device 12 is associated with the equalizing portion and application portion of the distributing valve device and in initiating a service application of the brakes functions, as will hereinafter more fully appear, to delay the application of the locomotive brakes for a chosen period of time.

10 1 This valve device 12 comprises a casing which in the present embodiment of the invention is secured to the casing of the equalizing portion of the distributing valve device, and also comprises a piston 55 having at one side a piston 15 chamber 56 which is connected to a passage 57 leading to the seat for the equalizing main slide valve 19. At the other side of the piston is a valve chamber 58 which is normally connected to a passage 59 leading to the seat for the slide 20 valve 19. Contained in the valve chamber 58 is a control slide valve 60 which is adapted to be actuated by the stem 61 of the piston 55. Contained in the piston chamber 56 is a spring 62 which at all times, tends to urge the piston toward its normal position, in which position the piston is shown in Fig. 2.

25 Contained in the valve chamber 58 of the valve device 12 is an expandable and rockable strut for exerting seating pressure on the control 30 slide valve 60. This strut comprises a part 63 which is rockably mounted on a pin 64 carried by the casing and also comprises a part 65 which engages the back surface of the slide valve 60 and which is slidably mounted in the part 63 so as to be freely movable in the direction of its length relative to the part 63. Interposed between and engaging said parts is a spring 66 which acts through the medium of the part 65 to urge the slide valve to its seat.

35 40 The release valve device 13 is provided for the purpose of controlling the release of the locomotive brakes independently of the operation of the equalizing portion of the distributing valve device, and since the details of its construction as well as its function have been fully covered in the aforementioned pending application Serial No. 619,052, a detailed description of the same in the present application is deemed unnecessary.

45 50 The change-over control valve device 8 is associated with the application portion of the distributing valve device, and as will hereinafter more fully appear, is selectively operative to one or the other of two positions to control the rate of increase in the pressure of application piston 55 chamber 33, thereby controlling the operation of the application portion and consequently the locomotive brakes in effecting an emergency application of the brakes. This valve device comprises a casing which in the present embodiment 60 of the invention is secured to the casing of the distributing valve device. The casing is provided with a piston chamber 67 which is connected through a passage and pipe 68 to the manually operable control valve device 9. Contained in the chamber 67 is a piston 69 having a stem 70 which is adapted to actuate a change-over slide valve 71 contained in a valve chamber 72 which is in constant open communication with the main reservoir 1 by way of a passage 73 and passage and pipe 54. Also contained in the piston chamber 67 is a spring 74 which engages the piston and tends to move the piston from the position in which it is shown in Fig. 2.

75 75 The manually operable control valve device 9

5 may comprise a casing, a plug valve 75 rotatably mounted in the casing and a handle 76 for rotating the valve. With the plug valve in the position shown in Fig. 1, the pipe 68 and consequently the piston chamber 67 of the change-over valve device is connected to the atmosphere through a passage 77 in the plug valve and a registering port 78 in the casing. When the handle 76 is turned to the position as shown by dotted lines in Fig. 1, the plug valve closes the communication from the pipe 68 to the atmospheric port 78 and the passage 77 in the valve establishes communication from the main reservoir pipe 54 to the pipe 68 as will hereinafter more fully appear.

10 15 In Fig. 1 of the drawings the automatic brake valve device 3 and the independent brake valve device 4 shown are each of the usual type, but it will be understood that any other desired type, such as is disclosed in a pending application of 20 Clyde C. Farmer, Serial No. 685,576, may be employed.

25 30 The automatic brake valve device shown comprises a casing having a rotary valve chamber 79 with which the main reservoir 1 is in constant open communication by way of pipe 54 and a passage 80. Contained in the chamber 79 is a rotary valve 81 having an operating stem 82 which is adapted to be rotated by means of a handle 83. The brake valve device also comprises 35 an equalizing discharge valve mechanism comprising a discharge valve 84 and a piston 85 for actuating the discharge valve.

40 35 The independent brake valve device comprises a casing having a rotary valve chamber 86 with 40 which the usual reducing valve device (not shown) is connected by way of a pipe 87. Contained in the chamber 86 is a rotary valve 88 having an operating stem 89 which is adapted to be rotated by a handle 90.

Initial charging

45 In charging the equipment, the independent brake valve device is in running position as shown and as is usual the rotary valve of the automatic brake valve device is turned first to release position and after a predetermined period of time has elapsed is then turned to running position.

50 55 With the automatic brake valve device in release position, fluid at main reservoir pressure flows from the rotary valve chamber 79 to the brake pipe 5 by way of a port 91 in the rotary valve 81 and a passage and pipe 92. Fluid under pressure supplied to the passage 92 flows to a chamber 93 at one side of the piston 85, and from the port 91 fluid under pressure flows through a passage 94 to a chamber 95 at the other side of the piston. From the piston chamber 95 fluid under pressure flows through a passage and pipe 96 to the equalizing reservoir 97.

60 65 Now when the rotary valve 81 is turned to running position the port 91 is lapped and the direct flow of fluid from the main reservoir 1 to the brake pipe 5 and equalizing discharge valve chambers 93 and 95 is closed off. Fluid under pressure does however flow from the feed valve device 2 to the brake pipe 5 by way of a pipe and passage 98, a cavity 99 in the rotary valve 81 and passage and pipe 92. From the passage 92 fluid under pressure flows to the chamber 93. From the cavity 99 fluid also flows through passage 94 to the piston chamber 95. Since the chambers 93 and 95 will be charged with fluid under pressure at substantially the same rate the force of gravity will maintain the exhaust valve 84 closed. 70 75 80 85 90 95 98 99 100

Fluid under pressure supplied to the brake pipe 5 flows therefrom through pipe and passage 17 to the equalizing piston chamber 16, and with the equalizing piston 15 in release position as shown in Fig. 2, fluid under pressure flows from the piston chamber 16 through a feed groove 100 around the piston 15, the opening in a choke plug 101 and a passage 102 to the equalizing valve chamber 18. From the chamber 18 fluid under pressure flows past the rear end of the main slide valve 19 and through passage 24, chamber 23 and passage 25 to the pressure chamber 26. It will thus be seen that the equalizing valve chamber 18 and pressure chamber 26 are charged with fluid to the pressure carried in the brake pipe.

With the equalizing slide valves 19 and 20 in release position and the change-over valve device 8 in position for short train operation, the application piston chamber 33 is open to the atmosphere by way of a passage 103, a cavity 104 in the change-over slide valve 71, passages 105, 106 and 107, a cavity 108 in the slide valve 60 of the reduction limiting valve device 12, a passage 109 having a choke plug 110 interposed therein, a pipe and passage 111, a cavity 112 in the rotary valve 88 of the independent brake valve device 4, passages and pipe 113, a cavity 114 in the rotary valve 81 of the automatic brake valve device 3 and a passage 115 leading to the atmosphere.

A cavity 116 in the equalizing main slide valve connects a passage 117 leading from the application chamber 118, to the passage 106, and since the latter passage is connected to the atmosphere in the manner just traced, the application chamber is of course open to the atmosphere.

With the change-over valve device 8 in position for long train operation, a cavity 119 in the change-over slide valve connects the passage 103 to a passage 120 which is connected to the passage 117 leading from the application chamber 118 so that the application piston chamber 33 is connected to the atmosphere by way of passage 117 and the connections therefrom to the atmosphere which have just been traced. The passage 103 is connected through a choked passage 121 to the passage 106 so that the application piston chamber is also open to the passage 106 which is open to the atmosphere as will be understood.

The reduction chamber 122 is connected to the atmosphere by way of a passage 123, a branch passage 124, a cavity 125 in the equalizing main slide valve 19 and a passage 126 leading to the atmosphere.

The piston chamber 56 of the reduction limiting valve device 12 is connected to the atmosphere by way of passage 57, a port 127 in the equalizing main slide valve 19, cavity 116 to which the port is connected, passage 106 and through the connections from the passage 106 as hereinbefore traced. The valve chamber 58 is connected to the cavity 116 through passage 59 and a port 128 in the main slide valve 19 and is therefore connected to the atmosphere by way of passage 106. With the chambers 56 and 58 thus connected to the atmosphere the spring 62 yieldably maintains the piston 55 and associated slide valve 60 in release position as shown in Fig. 2.

With the application piston 32 and the associated brake cylinder release valve 37 in release position as shown in Fig. 2, the brake cylinder 7 is open to the atmosphere by way of pipe and passage 39, release valve chamber 36 and a passage 129. Since the passage 41 is con-

nected to the passage 39, the chamber 34 is also connected to the atmosphere.

Fluid under pressure flows from the main reservoir by way of pipe and passage 54 to the application valve chambers 59 and 51. With the application piston in release position, the spring 45 and fluid under pressure in chamber 50 act to maintain the application valve seated so that the chambers 59 and 51 are charged with fluid at main reservoir pressure.

From the passage 54 fluid at main reservoir pressure flows through passage 73 to the valve chamber 72 of the change-over valve device 8 and holds the change-over piston and thereby the change-over slide valve 71 in the position shown in Fig. 2 against the opposing pressure of the spring 74 only, the piston chamber 67 being open to the atmosphere by way of passage and pipe 68, passage 77 in the valve device 9 and port 78.

Service application

When it is desired to effect a service application of the brakes on a train, the rotary valve 81 of the automatic brake valve device 3 is turned to service position in which a choked passage 130 leading from the equalizing discharge valve piston chamber 95 is connected by a cavity 131 in the rotary valve 81 to the atmospheric passage 115, so that the piston chamber is reduced at a service rate as governed by the choke in the passage 130. Fluid at brake pipe pressure in chamber 93 acting on the other side of the equalizing discharge valve piston 85 causes the piston to function in the usual manner to control the movement of the discharge valve 84 to vent fluid under pressure from the brake pipe and consequently from the equalizing piston chamber 16 of the distributing valve device at substantially the same rate as fluid is being vented from the piston chamber 95.

Upon a light gradual reduction in the pressure of fluid in the equalizing piston chamber 16, resulting from the venting of fluid from the chamber, the pressure of fluid in the equalizing valve chamber 18 causes the equalizing piston 15 to move outwardly to service position, in which position the piston is brought to a stop by the action of the spring stop 29.

The equalizing piston 15, in its traverse to service position, first closes communication between the piston chamber 16 and valve chamber 18 by way of the feed groove 100 and shifts the auxiliary slide valve 20 relative to the main slide valve 19 so as to uncover the usual restricted service port 132 in the main slide valve. The piston as it continues to move outwardly now moves the auxiliary and main slide valves 20 and 19, respectively, in unison toward service position. Upon the initial movement of the main slide valve the cavity 125 therein is moved out of registration with the atmospheric passage 126 and as a result the atmospheric communication from the reduction chamber 122 is discontinued, and then as the slide valve moves into service position, a cavity 133 in the main slide valve establishes communication from the passage 57 and thereby the reduction limiting valve piston chamber 56 to the passage 126 leading to the atmosphere so that the chamber 56 will be maintained at atmospheric pressure. At substantially the same time as the communication from the passage 57 to the passage 126 is established, a port 134 in the main slide valve

75

is opened to a passage 135 leading to the safety valve device 14. The port 134 is connected through a cavity 136 in the auxiliary slide valve 20 to a port 137 which leads to the cavity 116, 5 said connection having been previously established upon the movement of the auxiliary slide valve relatively to the main slide valve. Finally, the service port 132 opens to a toe cavity 138 of a passage 139 which is connected through 10 a cavity 140 in the control slide valve 60 of the reduction limiting valve device 12 and passage 123 to the reduction chamber 122, and since the service port 132 is open to the equalizing valve chamber 18 fluid under pressure now flows from 15 this valve chamber and pressure chamber 26 to the reduction chamber.

With the main slide valve 19 in service position the passage 124 leading from the passage 123 connected to the reduction chamber 122 is connected by the cavity 125 in the main slide valve to the passage 59 which leads to the valve chamber 58 so that fluid under pressure supplied from the equalizing piston chamber and pressure chamber 126 to the reduction chamber 122, by 20 way of passage 123, flows to the valve chamber 58.

Now when the fluid pressure in the reduction chamber has been increased to around fifty pounds, fluid at this pressure in the valve chamber 58, acting on a small area of the back of the piston 55 within a seat rib 142 against which the piston is held seated by the action of the spring 62, causes the piston to move out of seating engagement with the seat rib. Just as soon as the 30 seal between the piston and the seat rib is broken, fluid under pressure in the chamber 58 acts over the entire area of the back of the piston and causes the piston and thereby the control slide valve 60 to move with a snap action to their extreme outer position, the piston compressing the spring 62 and sealing against a gasket 143 as shown in Fig. 4.

The slide valve 60 in its traverse to the position in which it is shown in Fig. 4 laps the 45 passage 59, thus disestablishing the communication from the reduction chamber to the valve chamber 58 and at substantially the same time laps the release passage 109, thus disestablishing the communication from the application piston chamber 33 and application chamber 26 to this 50 release passage. At substantially the same time as these passages are lapped the slide valve uncovers one end of a passage 144. The other end of the passage being previously uncovered by the main slide valve 19, fluid under pressure flows 55 from the equalizing valve chamber 18 to the valve chamber 58 of the reduction limiting valve device. Further, the slide valve 60 in its traverse first disestablishes the communication between the passages 139 and 123 so that the flow of fluid 60 from the equalizing valve chamber 18 and pressure chamber to the reduction chamber is closed off, and then brings the cavity 108 into communication with the passage 139. Since the passage 65 107 is already in communication with the cavity 138, fluid under pressure now flows from the equalizing valve chamber 18 and connected pressure chamber 118 to the application piston chamber 33 by way of the service port 132 in the main equalizing slide valve 19, toe cavity 138, passage 139, cavity 108 in the control slide valve 60 of the reduction limiting valve device 12, passages 107, 106 and 105, cavity 104 in the slide valve 71 of the change-over valve device 8 and passage 103. Fluid under pressure may also flow through 75

the choked passage 121 from the passage 106 to the passage 103.

Fluid under pressure thus supplied to the passage 106 also flows to the application chamber 118 by way of cavity 116 in the main equalizing slide valve 19 and passage 117.

From the cavity 116 fluid under pressure also flows to the safety valve device 14 by way of port 137 in the equalizing main slide valve 19, cavity 136 in the equalizing auxiliary slide valve 20, 10 port 134 in the main slide valve and passage 135.

Fluid under pressure supplied to the application piston chamber 33 causes the application piston 32 to move inwardly, that is to say, in a direction toward the right hand, said piston, 15 through the medium of the piston stem 38, shifting the brake cylinder exhaust valve 37 to close the communication from the valve chamber 36 and connected brake cylinder 7 to the atmospheric exhaust passage 129.

As the piston continues to move in this direction, the end of the piston stem 38 engages and moves the valve piston 46 and thereby the gasket 47 out of seating engagement with the seat rib 48 against the resistance offered to such movement 25 by the spring 45 and the pressure of fluid in chamber 50. Fluid at main reservoir pressure now flows to the brake cylinder by way of pipe and passage 54, chamber 50, past the unseated valve piston and through passage and pipe 39. 30

From the passage 39, fluid under pressure also flows through passage 41 and the passage in the choke plug 42 to the chamber 34 at the back of the application piston 32.

When, with the valve piston 46 thus unseated, 35 the rate of increase in brake cylinder pressure substantially equals the rate of increase in the pressure of fluid in the application piston chamber 33, the application piston 32 will come to a stop, and the flow of fluid to the brake cylinder 40 at a rate corresponding to the rate of increase in the application piston chamber pressure continues.

From the foregoing description it will be seen that the equalizing portion of the distributing 45 valve device promptly moves to service application position following the initiation of a gradual reduction in brake pipe pressure, and that an application of the brakes is held back until a chosen fluid pressure, of for instance fifty pounds, 50 is obtained in the reduction reservoir 122.

It is well known that when a car brake cylinder piston is moved outwardly toward brake applying position by fluid supplied through the medium of a triple valve device, a certain amount 55 of fluid is required from the auxiliary reservoir to fill the vacuum space created by the movement of the brake cylinder piston before an effective braking force is applied to the car, while on the locomotive, since the application chamber 118 is initially at atmospheric pressure, fluid under pressure supplied to this chamber from the pressure chamber 26, in the absence of the reduction chamber 122 and reduction limiting valve device 12, would become immediately effective to operate the application portion of the distributing valve device to supply fluid under pressure to the locomotive brake cylinder, and for the same degree of reduction in the pressure of the pressure chamber as occurs in the auxiliary reservoir on the car, a higher pressure would be obtained in the application chamber 65 of the distributing valve device and consequently in the locomotive brake cylinder than is obtained in the car brake cylinder. This would, 70 75

of course, result in a more rapid retardation of the locomotive than of the cars, and such braking action tends to cause the slack in the train to run in or close toward the locomotive in a harsh and therefore dangerous manner.

In the present embodiment of the invention the volume of the reduction reservoir 122 is so proportioned to the combined volumes of the pressure chamber 26 and equalizing valve chamber 18 that when a pressure of approximately fifty pounds is obtained in the reduction chamber, a reduction of approximately five pounds is effected in the pressure of the pressure chamber 26, regardless of the pressure to which the pressure chamber is initially charged from the brake pipe. From this it will be evident that regardless of the brake pipe pressure normally carried the reduction limiting valve device 12 functions to limit the reduction in the pressure of the pressure chamber to around five pounds, which corresponds to the reduction required in the auxiliary reservoir on a car for moving the car brake cylinder piston to a brake applying position.

It will be seen that by holding back the initiation of an application of the locomotive brakes and by the reduction of the pressure chamber pressure an amount corresponding to the amount of reduction in auxiliary reservoir pressure required to initiate an effective braking action on a car, the locomotive brakes will be applied in substantial synchronization with the car brakes, and as a result the harsh slack run in or run out shocks, hereinbefore referred to are prevented.

When in effecting a limited application of the brakes, the pressure of fluid in the equalizing valve chamber 18 is reduced, by the flow of fluid therefrom to the application piston chamber 33 and application chamber 118, to a pressure slightly below the brake pipe pressure in the equalizing piston chamber 16, the equalizing piston 55 will be caused to move inwardly, that is to say in a direction toward the left hand, shifting the equalizing auxiliary slide valve 29 relative to the main slide valve 19 to first lap the port 134 which is in communication with the passage 135 leading to the safety valve device 14, and then lapping the service port 132 to close off any further flow of fluid from the equalizing valve chamber 18 and pressure chamber 26 to the application piston chamber 33 and application chamber 118. With the service port lapped, the pressures on opposite sides of the equalizing piston will be substantially equal, and due to this, the piston will come to a stop without moving the main slide valve out of its service position.

When, with the flow of fluid to the application piston chamber 33 and application chamber 118 thus closed off, the pressures on opposite sides of the application piston are substantially equal, the valve piston 46 will, under the influence of the action of the spring 45 and the pressure of fluid in chamber 50, be moved into seating engagement with the seat rib 48, the valve piston as it is thus moved, shifting the application piston forwardly to its lap position in which the brake cylinder exhaust valve 37 still maintains the communication closed from the brake cylinder to the atmospheric passage 129.

Release of brakes after a service application

When it is desired to release the brakes after a service application of the brakes has been effected, the rotary valve 81 of the automatic brake

valve device 3, as is the usual practice, is first turned to release position and then, after a predetermined period of time has elapsed, is turned to running position to effect the usual increase in brake pipe pressure. Since this increase in pressure is also effective in the equalizing piston chamber 16, the equalizing piston 15 and thereby the slide valves 19 and 29 are caused to move to release position, in which fluid under pressure in the valve chamber 58 of the reduction limiting valve device equalizes into the piston chamber 56 of the device by way of passage 144, a port 145 in the main slide valve 19, cavity 116, port 127 and passage 57.

With the fluid pressures on opposite sides of the piston 55 thus equalized, the spring 62 acts to shift the piston and thereby the control slide valve 60 to release position in which the cavity 108 again establishes communication between the passages 107 and 109 and in which the cavity 140 again establishes communication between the passages 123 and 139.

When the passages 107 and 109 are thus connected, fluid under pressure is vented from the application piston chamber 33 to the atmosphere by way of passage 103, cavity 104 in the change-over slide valve 71, passages 105, 106 and 107, cavity 108 in the slide valve 60, passage 109, pipe and passage 111, cavity 112 in the rotary valve 88 of the independent brake valve device, 30 with this brake valve device in running position, passages and pipe 113, cavity 114 in the rotary valve 81 of the automatic brake valve device and passage 115. Since the passage 117 leading from the application chamber 118 is connected by way of cavity 116 in the main slide valve 19 to the passage 106, fluid under pressure is also vented from the application chamber to the atmosphere. With the slide valve 60 of the reduction limiting valve device 12 in release position the valve chamber 58 is connected through passage 59 and port 128 to the cavity 116 in the main slide valve and fluid under pressure from said chamber is consequently vented to the atmosphere. The passage 57 leading from the piston chamber 56 of the valve device 12 is connected by way of port 127 to the cavity 116, so that fluid under pressure is also vented from this chamber to the atmosphere. Fluid under pressure is vented from the reduction chamber 122 by way of passages 123 and 124, cavity 125 in the main slide valve 19 and passage 126.

With the application piston chamber vented to the atmosphere, fluid at brake cylinder pressure in chambers 34 and 36 of the application portion causes the application piston 32 and thereby the brake cylinder exhaust valve 37 to move to release position, as shown in Fig. 2, in which position fluid under pressure is vented from the brake cylinder to the atmosphere by way of pipe and passage 39, brake cylinder exhaust valve chamber 36 and passage 35.

The several parts of the equipment being now in release position, the charging of the equipment will be the same as described in connection with the initial charging.

Emergency application of the brakes

In handling a short train such as is employed in passenger service and where the run-in of slack in the train is not sufficient to cause harsh damaging shocks, the plug valve is not moved from the position in which it is shown in Fig. 1 in effecting either a service or an emergency application of the brakes, and due to this, the

- emergency change-over valve device 8 will remain in the position in which it is shown in Fig. 2. However, in handling a long train of from one hundred to one hundred fifty or more cars where the slack in the train is sufficient to cause harsh dangerous shocks, the plug valve 75 of the valve device 9 is rotated 90° from the position in which it is shown in Fig. 1, preparatory to initiating an emergency reduction in brake pipe pressure. With the plug valve in this position, the communication from the pipe 68 and consequently from the piston chamber 67 of the change-over valve device 8 to the atmosphere by way of passage 77 and port 78 is disestablished and a communication is established by the passage 77 from the main reservoir pipe 54 to the pipe 68, through which communication fluid under pressure from the main reservoir 1 flows to the change-over piston chamber 67. Since the valve chamber 72 of the emergency change-over valve device 8 is charged with fluid at main reservoir pressure by way of passage 73, the fluid pressures on opposite sides of the change-over piston will be equal when fluid at main reservoir pressure is admitted to piston chamber 67, so that the spring 74 acts to shift the piston and thereby the change-over slide valve 71 to their innermost position in which the piston stops against a stop shoulder 146 formed on the casing of the device. With the slide valve 71 in this position the communication between the passage 103 and the passage 105 which by-passes the choked passage 121 is disestablished and the passage 103 is connected by cavity 119 in the slide valve to the passage 120 leading to the passage 117 which is connected to the application chamber 118.

Now when the rotary valve 81 of the automatic brake valve device is turned to emergency position, fluid under pressure is rapidly vented from the brake pipe to the atmosphere by way of pipe and passage 92, a cavity 147 in the rotary valve 81 and passage 115. The rapid reduction in brake pipe pressure causes a corresponding rapid reduction in the pressure of fluid in the equalizing piston chamber 16 and due to this, fluid under pressure in the equalizing valve chamber 18 causes the equalizing piston 15 and thereby the slide valves 19 and 20 to promptly move from release position to emergency position, the piston in emergency position overcoming the resistance offered by the spring-pressed stop 29 and engaging the gasket 28 as shown in Fig. 5.

In the emergency position of the main equalizing slide valve 19 fluid under pressure is permitted to flow from the equalizing valve chamber 18 and consequently from the pressure chamber 26 to the valve chamber 58 of the reduction limiting valve device 12 by way of passage 24, a port 147 in the main slide valve, cavity 125 and passage 59. The volume of the valve chamber is small, consequently a pressure in this chamber sufficient to move the piston 55 and thereby the control slide valve 60 to application position against the opposition offered by the spring 62 is quickly built up so that there is no material delay in the movement of the piston and slide valve to application position as there is in effecting a service application.

With the equalizing portion of the distributing valve device in emergency position and the reduction limiting valve device in application position, fluid under pressure flows from equalizing valve chamber 18 and pressure chamber 26 through an emergency port 148 and the service

port 132 in the main slide valve 19 to the cavity 138, and from thence flows through passage 139, cavity 108 in the slide valve 60 of the reduction limiting valve device 12, passages 107 and 106, choked passage 121 and passage 103. Fluid under pressure from the passage 103 also flows to the application chamber 118 by way of cavity 119 and passages 120 and 117. From an inspection of Fig. 5 it will be seen that in emergency position the main slide valve laps one end of the passage 1011 leading to the application chamber 118, thus preventing the flow of fluid from the passage 106 to the passage 117 by way of cavity 116 in the main slide valve. It will thus be seen that the flow of fluid under pressure to both the application piston chamber 33 and application chamber 118 can occur only by way of the restricted passage 121 and that the rate of increase in these chambers is governed according to the flow area of said passage.

Due to the restricted flow of fluid to the application piston chamber 33 and application chamber 118, the increase in the pressure of fluid in the application piston chamber 33 will be at a slower rate than would be the case if the restriction in the passage 121 and the connection from the application piston chamber to the application chamber were omitted.

Fluid under pressure supplied to the application piston chamber 33 causes the application piston 32 and thereby the brake cylinder exhaust valve 37 to move in the same manner as in effecting a service application of the brakes, the piston stem 38 engaging and moving the valve piston 46 away from the seat rib 48, permitting fluid at main reservoir pressure to flow to the brake cylinder 7.

With fluid under pressure being supplied to the brake cylinder, the application piston functions in the same manner as in effecting a service application of the brakes to control the operation of the valve piston 46 to regulate the rate of increase in brake cylinder pressure according to the rate of increase in the pressure of fluid in the application piston chamber 33, and since the rate of increase in the pressure of fluid in the application piston chamber 33, and since the rate of increase in the pressure of fluid in the application piston chamber is retarded, the rate of increase in brake cylinder pressure is correspondingly retarded.

Due to this, the braking power of the locomotive brakes, in effecting an emergency application of the brakes, will be increased in such a gradual manner as to materially contribute to the gentle gathering or closing of slack in the train.

It will here be noted that in effecting an emergency application of the brakes, the reduction limiting valve device will move so rapidly under the influence of pressure chamber pressure that there will be no appreciable flow of fluid from the equalizing valve chamber 18 and pressure chamber 26 to the reduction chamber by way of passage 139, cavity 140 in the slide valve 60 and passage 123, but it is not necessary that the reduction reservoir function to reduce the pressure chamber pressure in effecting an emergency application.

With the rotary valve 81 of the automatic brake valve device in emergency position, the feed valve passage 98 is connected through a cavity 150 in the rotary valve and a passage and pipe 151 to the application and release pipe 111, so that fluid at the pressure supplied by the feed valve device 2 is supplied to the equalizing valve chamber 18 and pressure chamber 26 by way of passage 109, a chamber 152 in the independent brake valve device 13, past the cut-off valve 153 of the device 13, 75

a chamber 154, a passage 155 and passage 107 which, at this time, is connected to the equalizing valve chamber and pressure chamber. Fluid under pressure thus supplied from the feed valve device 2 maintains the pressure in the equalizing valve chamber 18 and pressure chamber 26 against leakage of fluid from these chambers.

On a short train such as is employed in passenger service where the slack in the train is not great enough to cause harsh damaging shocks, the plug valve 75 is not turned from the position in which it is shown in Fig. 1 preparatory to effecting an emergency application, so that the emergency change-over valve device 8 will remain in the position in which it is shown in Fig. 1.

With the emergency change-over valve device in this position, the passage 119 connected to the application chamber 118 by way of passage 117 is blanked by the change-over slide valve 71 and the passage 103 leading to the application piston chamber 33 is connected by the cavity 120 in the slide valve to the passage 105.

When the several parts of the equalizing portion of the distributing valve device are shifted to emergency position, fluid under pressure is supplied through passages 106 and 105, cavity 120 in the change-over slide valve and passage 103. The main equalizing slide valve 19 in emergency positions laps the passage 117, so that fluid under pressure cannot flow from the passage 106 and cavity 116 to this passage and since the passage 120 is blanked there will be no flow of fluid from the equalizing valve chamber 18 and pressure chamber 26 to the application chamber 118, so that the increase in the pressure of fluid in the application piston chamber 33 and consequently in the brake cylinder 7 will be at a faster rate than when the application chamber is in communication with the application piston chamber.

Safety valve device

The safety valve device 14 is adapted to function in effecting either a service or an emergency application of the brakes to vent fluid under pressure from the equalizing piston chamber 18 and pressure chamber 26 when the pressure in these chambers exceeds the setting of the device to prevent an excessive brake cylinder pressure on the locomotive. Since this feature has been fully described in the aforementioned pending application, Serial No. 619,052, it is deemed unnecessary to repeat the description here.

Release of the brakes after an emergency application

If the plug valve 75 of the valve device 9 is in the position for long train operation, the engineer may, if he so desires, turn the valve to the position in which it is shown in Fig. 1, so as to vent fluid under pressure from the piston chamber 67 of the change-over valve device 8 to the atmosphere. With the chamber 67 thus vented, fluid at main reservoir pressure in chamber 12 causes the change-over piston 69 and thereby the slide valve to move outwardly, against the opposing pressure of the spring 74, to the position in which they are shown in Fig. 2.

Now when it is desired to release the brakes, the rotary valve of the automatic brake valve device 3 is turned to release position and then to running position in the usual manner to increase the brake pipe pressure. The increase in brake pipe pressure causes the several parts of the equipment to move to release position in substantially the same manner as hereinbefore described

in connection with the release of the brakes following a service application.

In long train operation, if the engineer fails to move the plug valve 75 to the position in which it is shown in Fig. 1, the release of fluid under pressure from the application piston chamber 33 will be by way of the restricted passage 121, but since the chamber 33 is of small volume the retardation in the reduction of application piston chamber pressure and consequent retardation of the reduction in locomotive brake cylinder pressure will be negligible, as will no doubt be readily understood.

The broad idea of controlling the rate of increase in the locomotive brake cylinder pressure in effecting an emergency application of the brakes and the idea of rendering such control either effective or ineffective is not claimed in the present application, since these features are the invention of Charles H. McKinstry, and are covered in his hereinbefore mentioned application, Serial No. 690,685, filed September 23, 1933.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. In a fluid pressure brake, the combination with a brake pipe and a chamber charged with fluid under pressure, of valve mechanism subject to the opposing pressures of the brake pipe and chamber and operated upon a reduction in brake pipe pressure for initiating a reduction in the pressure of fluid in the chamber, and means separate from said valve mechanism operable upon the operation of the valve mechanism for first limiting the reduction in the pressure of fluid in said chamber and for then supplying fluid under pressure from said chamber to cause an application of the brakes to be initiated.

2. In a fluid pressure brake, the combination with a brake pipe and a chamber charged with fluid under pressure, of valve mechanism subject to the opposing pressures of the brake pipe and chamber and operated upon a reduction in brake pipe pressure for initiating a reduction in the pressure of fluid in the chamber, and means separate from said valve mechanism operative only after the pressure of fluid in said chamber has been reduced a chosen amount for supplying fluid under pressure to cause an application of the brakes to be initiated, said means being cut in operation upon the operation of the valve means.

3. In a fluid pressure brake, the combination with a brake pipe and a chamber charged with fluid under pressure, of valve mechanism subject to the opposing pressures of the brake pipe and chamber and operated upon a reduction in brake pipe pressure for effecting a reduction in the pressure of fluid in the chamber, valve means separate from said valve mechanism operative to supply fluid under pressure from said chamber to cause an application of the brakes to be initiated, and means for delaying the operation of the valve means.

4. In a fluid pressure brake, the combination with a brake pipe and a chamber charged with fluid under pressure, of valve mechanism subject to the opposing pressures of the brake pipe and chamber and operated upon a reduction in brake pipe pressure for venting fluid under pres-

sure from said chamber to effect a reduction in the pressure of fluid in the chamber, and means responsive to the pressure of fluid vented from said chamber for first limiting the amount of fluid vented from said chamber and for then supplying fluid under pressure to cause an application of the brakes to be initiated.

5. In a fluid pressure brake, the combination with a brake pipe and a chamber charged with fluid under pressure, of valve mechanism subject to the opposing pressures of the brake pipe and chamber and operated upon a reduction in brake pipe pressure for venting fluid under pressure from said chamber to effect a reduction in the pressure of fluid in the chamber, a reduction reservoir, a valve normally establishing a communication through which fluid vented from said chamber by said valve mechanism flows to said reduction reservoir and operative to close said communication and to establish another communication through which fluid under pressure from said chamber is adapted to flow to cause an application of the brakes to be effected, a movable abutment responsive to the pressure of fluid vented from said chamber to said reservoir in effecting the reduction in the chamber pressure for actuating said valve, and means for delaying the movement of said abutment until the pressure of fluid acting thereon has been increased a chosen degree.

6. In a fluid pressure brake, the combination with a brake pipe, a chamber charged with fluid under pressure and a reduction reservoir, of valve mechanism subject to the opposing pressures of the brake pipe and chamber and operated upon a reduction in brake pipe pressure for venting fluid under pressure from said chamber to said reservoir, and means responsive to a chosen pressure in said reservoir for limiting the amount of fluid vented from said chamber and for establishing a communication through which fluid from said chamber flows to cause an application of the brakes to be effected.

7. In a fluid pressure brake, the combination with a brake pipe, a chamber charged with fluid under pressure and a reduction reservoir, of valve mechanism subject to the opposing pressures of the brake pipe and chamber and operated upon a reduction in brake pipe pressure for establishing a communication through which fluid under pressure is vented from said chamber, and valve means normally establishing a communication through which fluid under pressure is vented from said chamber to said reservoir and operative by fluid under pressure vented to said reservoir for disestablishing said communication to limit the reduction in the pressure of fluid in said chamber and for establishing another communication through which fluid vented from said chamber by way of the valve mechanism flows to cause an application of the brakes to be effected.

8. In a fluid pressure brake, the combination with a brake pipe, a chamber charged with fluid under pressure and a reduction reservoir, of valve mechanism subject to the opposing pressures of the brake pipe and chamber and normally establishing a communication from said reservoir to the atmosphere, said valve mechanism being operated upon a reduction in brake pipe pressure for first closing said communication and for then establishing another communication through which fluid under pressure is vented from said chamber, a valve normally establishing a communication through which fluid vented from said

chamber flows to said reservoir, and means responsive to a chosen reservoir pressure for actuating said valve to disestablish the last mentioned communication and to establish another communication through which fluid vented from said chamber by said valve mechanism flows to cause an application of the brakes to be effected.

9. In a fluid pressure brake, the combination with a brake pipe, a chamber charged with fluid under pressure and a reduction reservoir, of valve mechanism subject to the opposing pressures of the brake pipe and chamber and normally establishing a communication from said reservoir to the atmosphere, said valve mechanism being operated upon a reduction in brake pipe pressure for first closing said communication and for then establishing another communication through which fluid under pressure is vented from said chamber, a valve normally establishing a communication through which fluid vented from said chamber flows to said reservoir and being movable to a position for disestablishing the last mentioned communication and for establishing another communication through which fluid under pressure vented from said chamber by way of said valve mechanism flows to cause an application of the brakes to be effected, and means operative by fluid under pressure from said reservoir for moving said valve, the operation of said means being delayed until a chosen fluid pressure has been obtained in said reservoir.

10. In a fluid pressure brake, the combination with a brake pipe, a chamber charged with fluid under pressure and a reduction reservoir, of valve mechanism subject to the opposing pressures of the brake pipe and chamber and normally establishing a communication from said reservoir to the atmosphere, said valve mechanism being operated upon a reduction in brake pipe pressure for first closing said communication and for then establishing another communication through which fluid under pressure is vented from said chamber, a valve normally establishing a communication through which fluid vented from said chamber flows to said reservoir and being movable to a position for disestablishing the last mentioned communication and for establishing another communication through which fluid under pressure vented from said chamber by way of said valve mechanism flows to cause an application of the brakes to be effected, means operative by fluid under pressure from said reservoir for moving said valve, and yieldable resistance means for delaying the operation of said means until the pressure of fluid in said reservoir is increased to a chosen value.

11. In a fluid pressure brake, the combination with a brake pipe, a chamber charged with fluid under pressure and a reduction reservoir, of valve mechanism subject to the opposing pressures of the brake pipe and chamber and normally establishing a communication from said reservoir to the atmosphere, said valve mechanism being operated upon a reduction in brake pipe pressure for first closing said communication and for then establishing another communication through which fluid under pressure is vented from said chamber, a valve normally establishing a communication through which fluid vented from said chamber flows to said reservoir and being movable to a position for disestablishing the last mentioned communication and for establishing another communication through which fluid under pressure vented from said chamber

by way of said valve mechanism flows to cause an application of the brakes to be effected, means operative by fluid under pressure from said reservoir for moving said valve, and a spring for delaying the operation of said means until the pressure of fluid in said reservoir is increased to a chosen value.

12. In a fluid pressure brake, the combination with a brake pipe and a chamber charged with fluid under pressure, of valve mechanism subject to the opposing pressures of the brake pipe and chamber and operated upon a reduction in brake pipe pressure for venting fluid under pressure from said chamber to effect a reduction in the pressure of fluid in the chamber, and means responsive to the pressure of fluid vented from said chamber and regardless of the pressure to which the chamber is normally charged for first limiting the amount of fluid vented from the chamber and for then supplying fluid under pressure from the chamber to cause an application of the brakes to be effected.

13. In a fluid pressure brake, the combination with a brake pipe and a chamber charged with fluid under pressure, of valve mechanism subject to the opposing pressures of the brake pipe and chamber and operated upon a reduction in brake pipe pressure for venting fluid under pressure from said chamber to effect a reduction in the pressure of fluid in the chamber, and means responsive to the pressure of fluid vented from said chamber for first limiting the amount of fluid vented from said chamber regardless of the pressure to which the chamber is normally charged and for then supplying fluid under pressure to cause an application of the brakes to be effected.

14. In a fluid pressure brake, the combination with a brake pipe, a chamber charged with fluid under pressure and a reduction reservoir, of valve mechanism subject to the opposing pressures of the brake pipe and chamber and operated upon a reduction in brake pipe pressure for venting fluid under pressure from said chamber to said reservoir, and means responsive to a chosen pressure in said reservoir and regardless of the pressure to which the chamber is normally charged for limiting the amount of fluid vented from said chamber and for establishing a communication through which fluid from said chamber flows to cause an application of the brakes to be effected.

15. In a fluid pressure brake, the combination with a brake pipe, a chamber charged with fluid under pressure and a reduction reservoir, of valve mechanism subject to the opposing pressures of the brake pipe and chamber and normally establishing a communication from said reservoir to the atmosphere, said valve mechanism being operated upon a reduction in brake pipe pressure for first closing said communication and for then establishing another communication through which fluid under pressure is vented from said chamber, a valve normally establishing a communication through which fluid vented from said chamber flows to said reservoir and being movable to a position for disestablishing the last mentioned communication and for establishing another communication through which fluid under pressure vented from said chamber by way of said valve mechanism flows to cause an application of the brakes to be effected, and means operative only when the pressure of fluid in said reservoir is increased to a chosen value for moving said valve, said means being responsive to the

same reservoir pressure regardless of variations in the pressure of fluid normally carried in said chamber.

16. In a fluid pressure brake, the combination with a brake pipe, a chamber charged with fluid under pressure and a reduction reservoir normally communicating with the atmosphere, of a valve mechanism subject to the opposing pressures of the brake pipe and chamber and operative upon a reduction in brake pipe pressure for first disestablishing the communication from said reservoir to the atmosphere and for then establishing a communication through which fluid under pressure is vented from said chamber, a valve having means normally connecting the second mentioned communication to said reservoir to permit fluid vented from said chamber to flow to said reservoir, said valve being movable to a position for disconnecting the second mentioned communication from said reservoir and for establishing a connection through which fluid vented from said chamber by way of the second mentioned communication flows to cause an application of the brakes to be effected, and means operative by fluid under pressure from said reduction reservoir when the reduction reservoir pressure has been increased to a chosen value for moving said valve.

17. In a fluid pressure brake, the combination with a brake pipe, a chamber charged with fluid under pressure and a reduction reservoir normally communicating with the atmosphere, of a valve mechanism subject to the opposing pressures of the brake pipe and chamber and operative upon a reduction in brake pipe pressure for first disestablishing the communication from said reservoir to the atmosphere and for then establishing a communication through which fluid under pressure is vented from said chamber, a valve having means normally connecting the second mentioned communication to said reservoir to permit fluid vented from said chamber to flow to said reservoir, said valve being movable to a position for disconnecting the second mentioned communication from said reservoir and for establishing a connection through which fluid vented from said chamber by way of the second mentioned communication flows to cause an application of the brakes to be effected, means responsive to a chosen reduction reservoir pressure for moving said valve, and means for delaying the operation of said means until the chosen reduction reservoir pressure has been obtained.

18. In a fluid pressure brake, the combination with a brake pipe, a chamber charged with fluid under pressure and a reduction reservoir, of a valve mechanism subject to the opposing pressures of the brake pipe and chamber and operative upon a reduction in brake pipe pressure to a service application position for venting fluid under pressure from said chamber, means normally establishing a communication through which fluid vented from said chamber flows to said reservoir and operative upon an increase in the reduction reservoir pressure to a chosen degree to disestablish said communication and to establish a communication through which fluid vented from the chamber flows to cause an application of the brakes to be effected.

19. In a fluid pressure brake, the combination with a brake pipe, a chamber charged with fluid under pressure and a reduction reservoir, of a valve mechanism subject to the opposing pressures of the brake pipe and chamber and opera-

- tive upon a reduction in brake pipe pressure to a service application position for venting fluid under pressure from said chamber to said reservoir, and means responsive to a chosen reduction 5 reservoir pressure for closing off the flow of fluid to said reduction reservoir and for establishing a communication through which fluid from said chamber flows to cause an application of the brakes to be effected.
- 10 20. In a fluid pressure brake, the combination with a brake pipe, a pressure chamber and a reduction reservoir, of a valve device subject to the opposing pressures of the brake pipe and the pressure chamber and movable upon a reduction 15 in brake pipe pressure to a position in which communication is established from the pressure chamber to the reduction reservoir, and a valve device operated upon a predetermined increase in the pressure of fluid vented to the reduction 20 reservoir for cutting off said communication and for opening a communication through which fluid under pressure is supplied from the pressure chamber to effect an application of the brakes.
- 25 21. In a fluid pressure brake, the combination with a brake pipe, a pressure chamber and a reduction reservoir, of a valve device subject to the opposing pressures of the brake pipe and the pressure chamber and movable upon a reduction 30 in brake pipe pressure to service application position in which communication is established from the pressure chamber to the reduction reservoir, a valve operable for cutting off said communication and for opening a communication 35 through which fluid under pressure is supplied from the pressure chamber to effect an application of the brakes, and means operated upon a predetermined increase in the pressure of fluid in the reduction reservoir for actuating said 40 valve.
- 45 22. In a fluid pressure brake, the combination with a brake pipe, a pressure chamber and a reduction reservoir, of a valve device subject to the opposing pressures of the brake pipe and the pressure chamber and movable upon a reduction 50 in brake pipe pressure to service application position in which communication is established from the pressure chamber to the reduction reservoir, and a valve device operated upon a predetermined increase in the pressure of fluid vented to the reduction reservoir for cutting off said communication and for opening a communication 55 through which fluid under pressure is supplied from the pressure chamber to effect an application of the brakes, the first mentioned valve device being movable when the pressure chamber pressure is reduced slightly below that of the reduced brake pipe pressure from service application position to a position for closing off 60 the flow of fluid through the last mentioned communication.
- 65 23. In a fluid pressure brake, the combination with a brake pipe, a pressure chamber and a reduction reservoir, of a valve device subject to the opposing pressures of the brake pipe and the pressure chamber and movable upon a reduction 70 in brake pipe pressure to service application position in which communication is established from the pressure chamber to the reduction reservoir, and a valve device operated upon a predetermined increase in the pressure of fluid vented to the reduction reservoir for cutting off said communication and for opening a communication through which fluid under pressure is supplied from the 75 pressure chamber to effect an application of the brakes, the first mentioned valve device after having been moved to service application position being movable upon variations in brake pipe pressure and pressure chamber pressure for controlling the flow of fluid through the last mentioned communication.
- 80 24. In a fluid pressure brake, the combination with a brake pipe, a chamber charged with fluid under pressure and a reduction reservoir, of a valve mechanism subject to the opposing pressures of the brake pipe and chamber and operative upon a reduction in brake pipe pressure to a service application position for venting fluid under pressure from said chamber to said reservoir, and means responsive to a chosen reduction reservoir pressure for closing off the flow of fluid to said reduction reservoir and for establishing a communication through which fluid from said chamber flows to cause an application of the brakes to be effected and to disestablish a communication through which said means is subject to the reduction reservoir pressure and to establish a communication through which said means is subjected to the pressure of said chamber.
- 85 25. In a fluid pressure brake, the combination with a brake pipe and a chamber charged with fluid under pressure, of a reduction chamber, a distributing valve device comprising an equalizing portion subject to the opposing pressures of the brake pipe and chamber and operated upon a reduction in brake pipe pressure to serve application position for venting fluid under pressure from said chamber to said reservoir and operative upon an increase in brake pipe pressure to a brake releasing position, and also comprising an application portion adapted to be operated, when fluid under pressure is supplied to one side thereof, to effect an application of the brakes and adapted to be operated, upon the venting of fluid from said side, to effect the release of the brakes, 90 and valve means operated upon an increase in the pressure of said reservoir to first limit the amount of fluid vented from said chamber to the reservoir and to then supply fluid from said chamber to operate said application portion to effect an application of the brakes, said valve means being operative upon movement of the equalizing portion to release position for venting fluid under pressure to cause said application portion to operate to effect the release of the brakes.
- 95 26. In a fluid pressure brake, the combination with a brake pipe and a chamber charged with fluid under pressure, of a reduction chamber, a distributing valve device comprising an equalizing portion subject to the opposing pressures of the brake pipe and chamber and operated upon a reduction in brake pipe pressure to service application position for venting fluid under pressure from said chamber to said reservoir and operative upon an increase in brake pipe pressure to a brake releasing position, and also comprising an application portion adapted to be operated, when fluid under pressure is supplied to one side thereof, to effect an application of the brakes and adapted to be operated, upon the venting of fluid from said side, to effect the release of the brakes, a valve having a release position and an application position, said valve when in release position establishing communication through which fluid vented from said chamber flows to said reservoir and when in application position closing said communication and establishing another communication through which fluid under pressure is supplied by said equalizing portion to said side of the application.

portion, a spring, a movable abutment subject on one side to the pressure of fluid in said reservoir and subject on the other side to atmospheric pressure, and to the pressure of said spring and operative upon an increase in the pressure of said reservoir for moving said valve from release to application position, and means included in said equalizing portion operative in the release position of the equalizing portion for equalizing the fluid pressures on opposite sides of said abutment to permit said spring to act to move said abutment and thereby said valve from application position to release position, and means for venting fluid under pressure from the opposite sides of said abutment upon movement of the valve to release position.

27. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, valve mechanism operated upon a service reduction in brake pipe pressure for supplying fluid under pressure to both of said chambers and operative upon an emergency reduction in brake pipe pressure for supplying fluid under pressure to said piston chamber only, a fluid pressure controlled change-over valve device operable to one position for establishing a communication for connecting said chambers and operable to another position for disestablishing said communication, and a manually operable valve for controlling the operation of the change-over valve device.

28. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, valve mechanism operated upon a service reduction in brake pipe pressure for supplying fluid under pressure to both of said chambers and operative upon an emergency reduction in brake pipe pressure for supplying fluid under pressure to said piston chamber only, a fluid pressure controlled change-over valve device operable to one position for establishing a communication for connecting said chambers and operable to another position for disestablishing said communication, means for retarding the flow of fluid to said chambers when the change-over valve device is in the first mentioned position, said means being rendered ineffective to retard the flow of fluid to the application piston chamber when the change-over valve device is in the second mentioned position, and a manually operable valve for controlling the operation of the change-over valve device.

29. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, valve mechanism operated upon a service reduction in brake pipe pressure for supplying fluid under pressure to a passage leading to the application chamber and to another passage leading toward

the application piston chamber and operative upon an emergency reduction in brake pipe pressure for lapping the first mentioned passage, a fluid pressure controlled change-over valve device having two positions, said device functioning in one position to establish communication from the second mentioned passage to the application piston chamber, and functioning in the other position to establish a restricted communication from the second mentioned passage to both of said chambers, and a manually operative valve device for controlling the positioning of the change-over valve device. 5

30. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, valve mechanism operated upon a service reduction in brake pipe pressure for supplying fluid under pressure to a passage leading to the application chamber and to another passage leading toward the application piston chamber and operative upon an emergency reduction in brake pipe pressure for lapping the first mentioned passage, a fluid pressure controlled change-over valve device having two positions, said device functioning in one position to establish communication from the second mentioned passage to the application piston chamber, and functioning in the other position to establish a communication from the second mentioned passage to both of said chambers, 10 means for retarding the flow of fluid through said communication, said device in the other position functioning to establish a communication from the second mentioned passage to the application piston chamber, the last mentioned communication by-passing said means, and a manually operative valve device for controlling the positioning of the change-over valve device. 30

31. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, an equalizing valve device operable upon a service reduction in brake pipe pressure to a service application position in which said chambers are connected together, valve means operable after said equalizing valve device is in service position for supplying fluid under pressure to said connected chambers, said equalizing valve device being operated upon an emergency reduction in brake pipe pressure to emergency position in which said chambers are disconnected from each other and in which fluid under pressure is supplied to the application piston chamber only, and a change-over valve device operable to establish a restricted communication through which fluid supplied by said valve means flows to both of said chambers. 55

32. In a fluid pressure brake, the combination with a brake pipe, of a distributing valve device having an application chamber and an application piston chamber, valve means operative to effect an application of the brakes, an application piston in said piston chamber operative upon an increase in the pressure of fluid in the piston chamber for actuating said valve means, an equal- 70

- izing valve device operable upon a service reduction in brake pipe pressure to a service application position in which said chambers are connected together and operable upon an emergency 5 reduction in brake pipe pressure to emergency position in which said chambers are disconnected from each other and in which fluid under pressure is adapted to be supplied to the application piston chamber only, valve means operable after said 10 reduction in brake pipe pressure to emergency position for supplying fluid under pressure to both of said chambers or to one of said chambers according to the position of the equalizing valve device and means operable to a 15 position to establish a restricted communication through which fluid under pressure is adapted to flow to both of said chambers when the equalizing valve device is in emergency position and operable to a position for disestablishing said communication 20 and for establishing a communication through which fluid flows to the application piston chamber, the last mentioned communication by-passing the restricted portion of the first mentioned communication.
- 25 33. In a fluid pressure brake, in combination a brake pipe, a chamber charged with fluid under pressure, a valve mechanism subject to the opposing pressures of the brake pipe and chamber and operated upon a reduction in brake pipe pressure for supplying fluid under pressure from said chamber to cause an application of the brakes to be effected, means separate from said valve mechanism for controlling communication through which said valve mechanism supplies fluid to apply the brakes, and means for venting fluid from 30 said chamber before fluid under pressure is supplied to effect an application of the brakes.
34. In a fluid pressure brake, the combination with a brake pipe and a chamber charged with 40 fluid under pressure, of valve mechanism subject to the opposing pressures of the brake pipe and chamber and operated upon a reduction in brake pipe pressure for initiating a reduction in the pressure of fluid in the chamber, means separate from said valve mechanism operable for first limiting the reduction in the pressure of fluid in said chamber and for then supplying fluid to cause an application of the brakes to be effected, and pressure responsive means operative upon the operation of the valve mechanism to initiate a reduction in the pressure of fluid in said chamber for controlling the operation of said means.
35. In a fluid pressure brake, the combination with a brake pipe and a chamber charged with 45 fluid under pressure, of valve mechanism subject to the opposing pressures of the brake pipe and chamber and operated upon a reduction in brake pipe pressure for initiating a reduction in the pressure of fluid in the chamber, means separate from said valve mechanism operable for first limiting the reduction in the pressure of fluid in said chamber and for then supplying fluid to cause an application of the brakes to be effected, and means operative by fluid under pressure vented from 50 said chamber for actuating said means.
36. In a fluid pressure brake system for a train in combination, a brake pipe, a chamber charged with fluid under pressure, brake controlling apparatus on the locomotive operative upon a gradual reduction in brake pipe pressure to supply fluid under pressure from said chamber for effecting a service application of the brakes on the locomotive and upon a sudden reduction in brake pipe pressure for effecting an emergency application of 55 the brakes on the locomotive, means operative in effecting a service application of the brakes to reduce the pressure of fluid in said chamber an amount commensurate with the amount of reduction in the pressure of fluid in the auxiliary reservoir of a car of the train in taking up the lost motion in the car brake for causing the brakes on the locomotive to be applied in synchronism with the brakes on the cars of the train, and means operative in effecting an emergency application of 60 the brakes for causing the brakes on the locomotive to be applied at a rate not exceeding the emergency rate of an application of the brakes on the cars of the train.
37. In a fluid pressure brake system for a railway train, in combination, a brake pipe, a brake cylinder, a chamber charged with fluid under pressure, a brake controlling apparatus on the locomotive operative upon a gradual reduction in brake pipe pressure to supply fluid under pressure from said chamber for effecting a service application of the locomotive brakes and upon a sudden reduction in brake pipe pressure for effecting an emergency application of the locomotive 65 brakes, means operative in effecting a service application of the brakes to reduce the pressure of fluid in said chamber an amount commensurate with the amount of reduction in the pressure of fluid in the auxiliary reservoir of a car of the train in taking up the lost motion in the car brake for causing the brakes on the locomotive to be applied in synchronism with the brakes on the cars of the train, and means operative in effecting an emergency application of the brakes for causing a build up in pressure in said brake cylinder 70 at a rate not exceeding the emergency rate at which the brake cylinder pressure is built up on cars of the train.
38. In a fluid pressure brake system for a railway train, in combination, a brake pipe, a brake cylinder, a chamber charged with fluid under pressure, a brake controlling apparatus on the locomotive operative upon a gradual reduction in brake pipe pressure for supplying fluid under pressure from said chamber to cause the brake cylinder to effect a service application of the locomotive brakes and upon a sudden reduction in brake pipe pressure for supplying fluid under pressure from said chamber to cause the brake cylinder to effect an emergency application of the 75 locomotive brakes, means operative with the brake controlling apparatus in service application position to reduce the pressure of fluid in said chamber an amount commensurate with the amount of reduction in the pressure of fluid in the auxiliary reservoir of a car of the train in taking up the lost motion in the car brake for causing the brakes on the locomotive to be applied in synchronism with the brakes on cars of the train, and means operative with the brake controlling apparatus in emergency application position for retarding the rate of build up in pressure in the brake cylinder so as not to exceed the rate of brake cylinder pressure build up on cars of the train.
39. In a fluid pressure brake system for a railway train, in combination, a brake pipe, a brake cylinder on the locomotive, a chamber charged with fluid under pressure, a brake controlling apparatus subject to the opposing pressures of the brake pipe and chamber and operative upon a gradual reduction in brake pipe pressure for initiating a reduction in the pressure of fluid in said chamber and operative upon a sudden reduction in brake pipe pressure for supplying fluid under pressure from said chamber to cause the 80

operation of the brake cylinder to effect an emergency application of the locomotive brakes, means operative when the pressure of fluid in said chamber has been reduced an amount commensurate with the amount of reduction in the auxiliary reservoir pressure on a car of the train in taking up lost motion in the car brake for limiting the reduction in the pressure of fluid in the chamber and for supplying fluid under pressure from said chamber to cause the operation of the brake cylinder to effect a service application of the locomotive brakes, the reduced fluid pressure in said chamber and the action of said means causing the brakes on the locomotive to be applied in synchronism with the brakes on cars of the train, means operative in effecting an emergency application of the brakes for retarding the rate of increase in brake cylinder pressure so as not to exceed the rate of increase in brake cylinder pressure on cars of the train, and means included in the brake controlling apparatus for rendering the first mentioned means ineffective to control the supply of fluid under pressure in effecting an emergency application of the brakes.

40. In a fluid pressure brake system for a railway train, in combination, a brake pipe, a brake cylinder, a chamber charged with fluid under pressure, a brake controlling apparatus on the locomotive operative upon a gradual reduction in brake pipe pressure for supplying fluid under pressure from said chamber to cause the brake cylinder to effect a service application of the locomotive brakes and upon a sudden reduction in brake pipe pressure for supplying fluid under pressure to cause the brake cylinder to effect an emergency application of the locomotive brakes, means operative with the brake controlling apparatus in service application position to reduce the pressure of fluid in said chamber an amount commensurate with the amount of reduction in the pressure of fluid in the auxiliary reservoir of a car of the train in taking up lost motion in the car brake for causing the brakes on the locomotive to be applied in synchronism with the brakes on cars of the train, means operative with the brake controlling apparatus in emergency application position for retarding the rate of build up in pressure in the brake cylinder so as not to exceed the rate of brake cylinder pressure build up on cars of the train, and means for rendering ineffective the means for controlling the brake cylinder build up on the locomotive in emergency.

41. In a fluid pressure brake system for a railway train, in combination, a brake pipe, a brake cylinder, a chamber charged with fluid under pressure, a brake controlling apparatus on the locomotive operative upon a gradual reduction in brake pipe pressure for supplying fluid under pressure from said chamber to cause the brake cylinder to effect a service application of the locomotive brakes and upon a sudden reduction in brake pipe pressure for supplying fluid under pressure to cause the brake cylinder to effect an emergency application of the locomotive brakes, means operative with the brake controlling apparatus in service application position to reduce the pressure of fluid in said chamber an amount

commensurate with the amount of reduction in the pressure of fluid in the auxiliary reservoir of a car of the train in taking up lost motion in the car brake for causing the brakes on the locomotive to be applied in synchronism with the brakes on cars of the train, means operative with the brake controlling apparatus in emergency application position for retarding the rate of build up in pressure in the brake cylinder so as not to exceed the rate of brake cylinder pressure build up on cars of the train, fluid pressure controlled means for rendering ineffective the means for controlling the brake cylinder build up in emergency, and means operative to control the pressure of fluid acting on the fluid pressure controlled means.

42. In a fluid pressure brake system for a railway train, in combination, a brake pipe, a brake cylinder, a chamber charged with fluid under pressure, a brake controlling apparatus on the locomotive operative upon a gradual reduction in brake pipe pressure for supplying fluid under pressure to cause the brake cylinder to effect a service application of the locomotive brakes and upon a sudden reduction in brake pipe pressure for supplying fluid under pressure from said chamber to cause the brake cylinder to effect an emergency application of the locomotive brakes, means operative with the brake controlling apparatus in service application position to reduce the pressure of fluid in said chamber an amount commensurate with the amount of reduction in the pressure of fluid in the auxiliary reservoir of a car of the train in taking up lost motion in the car brake for causing the brakes on the locomotive to be applied in synchronism with the brakes on cars of the train, means operative with the brake controlling apparatus in emergency application position for retarding the rate of build up in pressure in the brake cylinder so as not to exceed the rate of brake cylinder pressure build up on cars of the train, fluid pressure controlled means for rendering ineffective the means for controlling the brake cylinder build up in emergency, and a manually operative valve device for controlling the operation of said fluid pressure controlled means.

43. In a fluid pressure brake, in combination, a brake pipe, a chamber charged with fluid under pressure, a brake controlling valve mechanism subject to the opposing pressures of the brake pipe and chamber and operative upon a reduction in brake pipe pressure for initiating a reduction in the pressure of fluid in said chamber, means operative to first limit the reduction in the pressure of fluid in said chamber to an amount commensurate with the amount of reduction in the pressure of fluid in the auxiliary reservoir of a car of a train in taking up the lost motion in the car brakes, and to then supply fluid under pressure from said chamber to effect an application of the brakes, and means separate from the brake controlling valve mechanism and set in operation upon the operation of the brake controlling valve mechanism for controlling the operation of the first mentioned means.

ELLIS E. HEWITT.
